Primary Examiner—Dominic Simone

(57) **CLAIM**

The ornamental design is for a rattle element for a toy, as shown and described.

DESCRIPTION

FIG. 1 is a perspective view of said design;
FIG. 2 is an end view of said design, the other end being a mirror image;
FIG. 3 is a left side view thereof, the right side being a mirror image;

FIG. 4 is a bottom view thereof;
FIG. 5 is a left side view thereof, showing shiftable rattle elements on the interior thereof; and,
FIG. 6 is a view similar to the view of FIG. 5, but with the rattle element tilted.
